UNITED STATES PATENT OFFICE.

JOHN L. HANMER, OF BURLINGAME, KANSAS.

END-GATE FASTENER.

SPECIFICATION forming part of Letters Patent No. 365,992, dated July 5, 1887.

Application filed October 20, 1886. Serial No. 216,723. (No model.)

To all whom it may concern:

Be it known that I, JOHN L. HANMER, of Burlingame, in the county of Osage and State of Kansas, have invented a new and Improved 5 End-Gate Fastener, of which the following is a full, clear, and exact description.

The object of my invention is to provide a new and improved end-gate fastener which is simple and durable in construction and permits of removing the end-gate quickly.

The invention consists of a spring attached across the end-gate near its top and of a device for holding and locking the gate in place.

The invention also consists of various parts 15 and details and combinations of the same, as will be fully described hereinafter, and then pointed out in the claims.

Reference is to be had to the accompanying drawings, forming a part of this specification, 20 in which similar letters of reference indicate corresponding parts in all the figures.

Figure 1 is an end view of a wagon-bed provided with my improvement, parts being broken out. Fig. 2 is a plan view of the same, 25 parts being in section. Fig. 3 is a sectional side elevation of the same on the line $\alpha\alpha$ of Fig. 1. Fig. 4 is a plan view of a modification, and Fig. 5 is a sectional side elevation of the same.

30 The wagon-bed A, of any approved construction, is provided with the sides B and bottom C, each of the sides B being provided near its rear end with an upright L-shaped cleat, D, and a square cleat, E, both forming 35 a pocket or recess, F. The end-gate G is provided on its outer side with vertical bars G', to which is secured, near the upper edges of said bars, a spring-plate, H, carrying on each outer end a lug, I, which fits into the pocket or recess F. On each of the L-shaped cleats D is pivoted a hook, J, which hooks over the upper edge of the spring-plate H. It will be seen that the lugs I, fitting into the pockets F, hold the end-gate G on the rear of the wagon-bed A, and the hooks J lock the end-gate in 45

position and prevent an upward sliding motion of the same. When it is desirable to remove the end-gate G, the hooks J are disengaged from the spring-plate H and the gate is lifted upward until the lugs I are out of the 50 pockets F, whereby the gate G is set free.

In the modifications shown in Figs. 4 and 5, I attach to the square cleat K, which takes the place of the L-shaped cleat D, a block, L, having a notch, L', into which fits the spring 55 M, secured to the spring-plate H, thus preventing the gate from sliding upward.

Having thus described my invention, what I claim as new, and desire to secure by Letters Patent, is—

1. The combination, with a wagon-bed provided with two upright cleats on the inner surface of its rear end, one of the said uprights being provided with a recess, of an end-gate resting against the inner surface of the inner 65 cleat and provided with a horizontal plate having lugs on its end projecting into the pocket formed by the said cleats, substantially as herein shown and described.

2. The combination, with a wagon-bed provided with the L-shaped cleat D and the cleat E, forming a pocket, F, of the end-gate G, the horizontal bar H, secured to the gate and provided with the lugs I at its end, and means for preventing vertical movement of the end-gate, substantially as herein shown and described.

3. The combination, with a wagon-bed provided with the cleats D E, the cleat D being L-shaped, and forming with the cleat E the 80 pocket F, of the end-gate G, the horizontal bar H, having lugs I on its ends, and the hooks J, pivoted to the cleats D and engaging the edge of the bar H, substantially as herein shown and described.

JOHN L. HANMER.
